UNITED STATES PATENT OFFICE.

JAMES N. MOULTON, OF HAVERHILL, ASSIGNOR TO THE STANLEY MANUFACTURING COMPANY, OF BOSTON, MASSACHUSETTS.

SOLE-ROUNDING MACHINE.

SPECIFICATION forming part of Letters Patent No. 522,166, dated June 26, 1894.

Application filed September 25, 1893. Serial No. 486,366. (No model.)

To all whom it may concern:

Be it known that I, JAMES N. MOULTON, of Haverhill, county of Essex, State of Massachusetts, have invented an Improvement in Sole-Rounding Machines, of which the following description, in connection with the accompanying drawings, is a specification, like letters and figures on the drawings representing like parts.

10 This invention has for its object the production of a novel machine for rounding or shaping soles, my said machine being adapted to shape the sole from a block of leather, and with but slight adjustments, from a strip of 15 leather.

15 In my improved machine the material for the sole is held between a clamping plate and a pattern plate, and a knife pivoted upon a knife plate adapted to slide horizontally in

20 guide-ways of a carriage pivoted on a shoe fitted to slide in guide-ways of an arm, is made to travel about said pattern plate and cut the leather thereon into sole-shape as the said arm is revolved about the pattern plate.

25 The carriage referred to has two roller or other studs which enter a cam shaped groove in a stationary cam-plate located below the pattern-plate on which the leather rests, and the pivot of the said carriage is located at a 30 distance back of a line intersecting the centers of said rolls, such location of the pivot of the carriage enabling it to be moved steadily and uniformly at all points of its travel about the pattern plate.

35 In my machine the knife-bar may have a long range of movement toward and from the center of the pattern plate, which is stationary, and the knife bar is acted upon by a spring-controlled lever, and a suitable connection between it and the knife bar, whereby the knife bar, as it travels about the stationary pattern plate, may adapt itself to whatever size or shape of plate is used, the cam plate serving for different sizes and shapes of soles without any change or adjustment of its position.

40 One part of my invention consists essentially in a sole rounding machine containing the following instrumentalities, viz:—a stationary pattern plate upon which the leather

5 to be cut is held fixedly; a stationary cam plate having a cam groove; a rotatable arm as d^4 having a guideway; a bar adapted to slide therein longitudinally; a carriage pivoted to said bar and provided with roller or other 55 studs to enter the groove of the said cam plate; a knife-bar fitted to slide in guideways connected with said carriage; a knife-holder carried by said knife-bar; means to keep the said knife-holder pressed up to the said 60 pattern plate and yet adapt it to follow the contour of the pattern plate of whatever form; and means to rotate said arm and move said carriage with the said knife about the pattern plate, substantially as will be described.

65 Other features of my invention will be hereinafter described and particularly pointed out in the claims.

70 Figure 1, in side elevation shows one form of my improved sole rounding machine adapted to shape soles from blocks of leather; Fig. 1^a, an enlarged section of block h^9 . Fig. 2 is a partial front view of the machine shown in Fig. 1. Fig. 2^a is a detail of the lower end of 75 the locking device detached from Fig. 2, together with a small part of the presser-plate. Fig. 3 is a plan view looking down below the line x , Fig. 2, the pattern plate, and the pattern plate rest, being partially broken out to 80 show the bolt below them; Fig. 3^a a detail of the knife and knife holder. Fig. 4 is an under side view of the parts shown in Fig. 3. Fig. 5 is a detail, looking from the under side 85 of the machine, of some of the devices for pulling the knife-bar back from the pattern plate when the latter is to be changed for another of a different shape. Fig. 6 is a detail looking down below the line x^3 Fig. 1, on the locking mechanism to be described, the said 90 figure, however, showing the parts in a position different from the position Fig. 1; Fig. 7 a detail showing the top of the post d^2 , part of the hub of the gear E' , and the hub and arm d^3, d^4 .

95 The frame-work consists essentially of a column A upon which is mounted a head or neck A', the latter containing bearings for the working parts to be described. The upper part of the head has suitable bearings for 100

a presser rod B provided at its lower end with a yoke-shaped presser carrier B' pivoted thereto at B², said carrier having detachably connected with it a presser plate B³, the plate 5 being locked to the carrier by means of a suitable locking device B⁴, herein shown as a spring, which enters a hole in said plate, the said locking device, see Fig. 2^a, having near its free end a notch to engage a portion of 10 said presser-plate, the said locking device providing for the ready removal of one presser plate of one size or shape, and the substitution of another presser plate of a different size or shape. The carrier referred to, at or 15 near its pivotal point, has co-operating with it a suitable evener B⁵, shown as a spring, which abuts against a shoulder carried by the presser rod B, one end of said spring being connected by a screw 30 to yoke B':

20 The presser rod B has fixed upon it in adjustable manner a collar B⁶, having preferably a projection slotted or grooved to embrace a guide B⁷ connected to or forming a part of the head A', said guide insuring the 25 retention of the presser plate in exactly the proper position; but by loosening the set screw B⁸ the presser rod may be turned therein more or less to place the presser plate in a position ninety degrees farther around than in 30 the drawings, for purposes to be hereinafter described.

The presser rod is normally kept elevated by a suitable spring B⁹ acting against the said collar and against a portion of the head. 35 The head has a suitable pivot C on which is mounted a presser lever C' having jointed to it a rod C² suitably threaded at or near its lower end to receive upon it an adjusting nut C³, the rod below said nut being surrounded 40 by a spring C⁴ which is represented as resting on a collar C⁵ loose on said rod, said carrier being acted upon by one arm of the treadle lever C⁶ pivoted at C⁷, said arm also having in it a suitable hole to receive and 45 guide the lower end of the rod C², as represented by dotted lines in Fig. 1.

The main shaft D of the machine has fast upon it a brake wheel D', and the fixed part D² of a friction or clutch pulley with which 50 co-operates the continuously running or movable part D³ of said clutch pulley, the said pulleys having preferably conical faces to afford the proper frictional engagement, in usual manner. The main shaft is partially 55 surrounded between the brake pulley and the loose pulley of the friction clutch with a beveled fork D⁴ connected to a vertically moving rod D⁵, the threaded lower end of which is also extended, see Fig. 1, through a 60 hole in one arm of the treadle C⁶, a spring D⁶ acting normally to keep the said wedge down in the position shown in Fig. 1, at which time the friction pulley will be unclutched and the shaft at rest.

65 The rod D⁵ has upon its threaded portion an adjustable nut or collar D⁷, the change of position of which vertically, enables the lever

C⁶ to contact with the said collar sooner or later to thus give the proper throw to the wedge D⁴ to thus insure the starting of the 70 main shaft at the proper instant of time.

The rod D⁵, or the part thereof below the wedge D⁴ has a brake-arm D⁸ suitably shaped, see Fig. 1, to engage a V- or equivalent shaped groove at one side of the brake pulley, and 75 stop the machine instantly when the treadle is released to let the wedge D⁴ drop, as will be described.

The treadle C⁶ has a horn c forming one part of a locking device, the other part being a hook c' attached to a rod c² having suitable bearings at c³, the upper end of said rod having fast upon it an arm c⁴ against which acts a lug or projection c⁵ carried by the downwardly extended hub E forming part of 85 the bevel gear E', to be described, said projection striking a suitable projection on said arm c⁴ and causing the hook c' to be turned from its position Fig. 6 and release the lever C⁶ once during each rotation of the gear E', 90 letting the said lever assume its starting position, which will be with the inner end of the treadle down. The rod c² is surrounded by a suitable spring c⁸ which is connected one end to the arm c⁴ and the other to the bearing c³, said spring normally acting to keep the arm c⁴ pressed toward and in the path of movement of the projection c⁵.

The main shaft D has upon its inner end a bevel gear d which engages the bevel gear E', 100 it rotating about a fixed stud d², the upwardly extended part of the hub E of said bevel gear E' having clamped upon it, in this present instance of my invention, the split hub d³ of the arm d⁴, to be described, said hub being 105 confined in position by a suitable screw d⁵. The hub of the gear E' has extended upwardly from it a stop-bar d⁶, see the detail Fig. 7, said stop-bar being also shown in Fig. 1, said stop-bar by contact with the under 110 side of the cam-plate F preventing the rising of the gear E' under the strains to which it is subjected in the act of being rotated. The post d² referred to, has at its upper end four 115 positioning holes 3, 4, 5, 6, and a tapped hole 7, the tapped hole receiving the bolt d¹⁰, which serves to fix the cam plate F in its operative position. The cam plate has at its under 120 side, see Fig. 4, registering pins 8, 9, which enter either of the pair of holes 3, 4, or the 125 pair of holes 5, 6, according to whether the pattern plate is to stand lengthwise or crosswise with relation to the frame of the machine, it standing crosswise, as in the drawings, when the soles are to be shaped from 130 blocks of leather, or standing lengthwise, or ninety degrees farther around, when soles are to be cut from strips of leather the width of which corresponds with or is a little wider than the length of the soles to be cut therefrom. The cam-plate has at its under side the groove f. The cam-plate receives and holds two like studs 12, 13, upon which is mounted a pattern rest g upon which is laid

and supported firmly the pattern plate g' , the upper ends of the studs 12, 13, entering holes in the said pattern plate.

In Fig. 3 I have broken away the pattern plate and part of the pattern rest below it to better show the bolt d^{10} , hereinbefore referred to.

The arm d^4 , as best shown in Fig. 3, has a suitable guideway, as d^{12} , see Fig. 2, in which is fitted to slide the foot plate h upon which is pivoted at h' , see Fig. 4, the carriage H provided with the roller or other studs h^2, h^3 , which enter the groove f of the cam-plate, the said roller or other studs being nearer the end of the carriage than the pivotal point thereof, such location of the roller studs with relation to the pivotal point of the carriage insuring, even with the fixed cam-plate, a steady uniform movement of the said carriage, and a uniform action of its knife, to be described, as the carriage is carried about the said cam plate with the slide h in the groove of the arm d^4 , through the agency of the gears d , E' , the said carriage during this operation sliding backward and forward, the plate h sliding in the groove of the arm d^4 under the control of a strong spring h^5 fixed at one end to the carriage H and its other end to an arm or lever h^6 pivoted upon the stud h^7 erected on the carriage H , the free end of said arm or lever being herein represented as provided with a hole to receive one end of a connecting rod h^8 , the other end of which is joined to the block h^9 which rises from the knife-bar h^{10} , fitted to slide in suitable guideways in the upper portion of the carriage, H . The block h^9 is provided with a suitable hole to receive the shank h^{20} , see Fig. 3^a, of the knife carrier h^{12} provided with a knife h^{13} , the said knife-carrier and knife being represented best in Fig. 3^a, the hole, see Fig. 1^a receiving a steel bushing s^2 . By the employment of a spring such as h^5 , located at a distance from the knife, and interposing between the said spring, an arm and connecting mechanism, a sufficient range of movement is given to the knife bar h^{10} so that it may follow the pattern plate, of whatever size used, it being understood that one pattern plate may be removed and another substituted for it of a different size and shape as required.

When a pattern plate is to be changed the operator will engage the handle m pivoted at m' to a portion of the carriage H , as shown best in Figs. 4 and 5, and will turn said handle in the direction of the arrow thereon until the slotted portion m^2 , jointed to a portion of the said handle at m^3 , meets a pin m^4 connected to the knife-bar, when thereafter the knife-bar will be drawn back away from the pattern plate.

In practice I provide a suitable spring as m^5 to act upon the handle and hold it in its normal position shown in said figures.

If it is desired to cut soles from a strip as stated, the operator will, as stated, release

the screw B^8 and turn the presser rod B about for ninety degrees, and will then release the bolt, d^{10} , lift the cam-plate F from the top of the post d^3 , and turn the cam plate around for ninety degrees and secure it in that position as before by the bolt d^{10} . In order that the knife may be made to commence to cut the leather at any desired point with relation to the pattern plate, the operator will release the screw d^5 and turn the split hub d^3 of the arm d^4 about the hub E . In practice the knife is usually made to stop at or about the junction of the ball of the heel, or at the point marked n see Fig. 3, rather than in the position shown as occupied by the knife in said figure. Assuming that the knife is in proper starting position and the machine at rest, the operator will put his foot upon the treadle, 85 depress its outer end and in so doing the treadle will first act upon the collar C^6 , and through the spring C^4 will cause the lever C' to depress the presser bar B and cause the presser plate B^3 to descend upon the blank 90 of leather s previously laid upon the pattern plate, the further depression of the lever causing its rear end to meet the collar D^7 , elevate the wedge D^4 , and force the clutch pulley parts in contact so that the main shaft 95 will be started. The main shaft in its movement will revolve the gear E' in the direction of the arrow upon it. When the knife starts from the position designated by n , the projection c^5 will stand about in the position 100 designated by the dotted lines n' , Fig. 6, and when the said projection in its rotation in the direction of the arrow near the hub E meets the projection 30 of the arm c^4 the locking device c' will be turned to release the 105 treadle C^6 , as before described, letting the springs C^4, B^9 , acting in conjunction, lower the rear end of the treadle.

I have aimed to produce a practical sole rounding machine with the fewest possible parts and with the simplest possible mechanism, to thereby produce a durable, efficient, and easily adjusted machine, and while I have specifically described the various parts, this invention is not to be limited to the construction of the mechanism shown, as it will be obvious to those familiar with the art that modifications in form and shape might be made, calling only for usual mechanical skill, without departing from my invention. By 110 the employment of the tubular steel bushing s^2 in the block h^9 , which bushing receives the knife shank h^{20} , the block is not worn and a bushing when worn may be readily removed and a new bushing substituted for it. It is 115 quite essential that the shank of the blade be held without unnecessary looseness so that the knife can wobble.

The steel bushing as shown in Fig. 1^a is provided with a suitable hole for the insertion of 120 the usual pin which by entering the groove in the knife shank prevents vertical movement of the knife.

Having described my invention, what I

claim as new, and desire to secure by Letters Patent, is—

1. A sole rounding machine containing the following instrumentalities, viz:—a stationary pattern plate upon which the leather to be cut is held fixedly; a stationary cam plate having a cam groove; a rotatable arm as d^4 having a guideway; a bar adapted to slide therein longitudinally; a carriage pivoted to said bar and provided with roller or other studs to enter the groove of the said cam plate; a knife bar fitted to slide in guideways connected with said carriage; a knife holder carried by said knife bar; means to keep the said knife-holder pressed up to the said pattern plate and yet adapt it to follow the contour of the pattern plate of whatever form; and means to rotate said arm and move said carriage with the said knife about the pattern plate, substantially as described.
2. In a sole rounding machine, the following instrumentalities, viz:—a stationary pattern plate; a stationary cam-plate provided with a groove; a pivoted carriage having roller or other studs to enter the grooves of the cam plate and provided with a guideway at its upper side; a knife-bar mounted to slide in said guideway; a knife holder and knife pivotally mounted in said bar; and a lever and link connecting operating with said knife-bar; combined with a spring as h^5 whereby great latitude of horizontal movement is permitted to said knife-bar with relation to the longitudinal center of the cam-plate whereby said spring, lever, and connections adapt the knife to co-operate with pattern plates of different sizes, the carriage being under the control of one and the same stationary cam, substantially as described.
3. In a sole rounding machine, the gear E' having a hub E ; a post to support said gear hub; combined with an arm as d^4 the hub of which surrounds and is clamped adjustably upon the hub of the gear, said arm forming a support for the knife carriage, the adjustment of the said arm about said hub when not clamped thereto enabling the position of the carriage to be adjusted with relation to the pattern plate, substantially as described.
4. In a sole rounding machine, a stationary pattern plate, a presser bar, and a carrier pivoted thereon, combined with a detachable presser plate, and a locking device therefor, to operate substantially as described.
5. The stationary pattern plate of a sole rounding machine; the presser-bar, and a yoke-shaped carrier pivoted thereon; and its connected presser plate; combined with the evener spring to adapt the presser plate to

variations in thickness of the leather lying between it and the pattern plate, substantially as described.

6. In a sole rounding machine, the following instrumentalities, viz:—a stationary pattern plate to sustain the leather to be cut; a cam plate; a knife-bar and knife; a gear E' having a projection; devices actuated by said gear to carry the said knife-bar once around said pattern plate; a presser bar having a suitable presser plate; a spring to normally elevate the presser-bar; the main shaft of the machine; a clutch-pulley mounted thereon; means to effect the engagement of said clutch pulleys to start the said main shaft, said means having a collar D^7 ; a treadle under the control of the foot of the operator; devices intermediate said treadle and said presser-bar to depress the latter; a locking device co-operating with a part of said treadle; and a gear connected with said main shaft to rotate the gear E' , whereby when the operator actuates the treadle the presser-bar is first depressed to clamp the leather between itself and the pattern plate, and the clutch pulleys are thereafter engaged to effect the rotation of the main shaft, and the said treadle is locked in position by the locking device until the main shaft has rotated the gear E' once, when the projection movable with said gear effects the unlocking of the treadle and the stopping of the machine, substantially as described.

7. In a sole rounding machine, the gear E' having its hub provided with a projection d^x ; an arm d^4 connected with a portion of the hub of said gear and forming a support for a carriage containing a knife-bar and rounding knife; a pattern plate to sustain the material to be cut; a presser plate to rest on said material; its carrying bar and elevating spring, combined with a treadle having a locking projection c , a lever to act on said bar, a rod connected to said lever and extended to said treadle, a spring interposed between said treadle and rod, and with a locking device intermediate said gear and said projection whereby as the said gear completes a rotation, the locking device is turned to effect the release of the treadle, and enable the presser bar and plate to be automatically lifted, substantially as described.

In testimony whereof I have signed my name to this specification in the presence of two subscribing witnesses.

JAMES N. MOULTON.
